(57) **CLAIM**

The ornamental design for a wheel, as shown and described.

DESCRIPTION

FIG. 1 is a front left perspective view of a wheel for a vehicle according to the present invention.

FIG. 2 is a front view of the wheel shown in FIG. 1

FIG. 3 is a left side view thereof, the right side view being a mirror image thereof.

FIG. 4 is a front left perspective view of a wheel for a vehicle according a second embodiment of the present invention.

FIG. 5 is a front view of the wheel shown in FIG. 4; and, FIG. 6 is a left side view thereof, the right side view being a mirror image thereof.

The broken lines depict portions of the wheel that form no part of the claim.
